THOMAS N. BROWN, OF FORT WAYNE, INDIANA.

IRONING MACHINE.

Application filed August 16, 1926. Serial No. 129,300.

The invention relates to ironing machines and particularly to the driving mechanism thereof.

The object of the invention is to provide an efficient machine in which the ironing rollers are shifted and operated in novel manner.

The invention consists in the novel combination and arrangement of parts herein-
10 after described, an embodiment of which is illustrated in the drawings, in which draw-
ings

Figure 1 is a perspective view of a machine embodying the invention; Fig. 2 a rear elevational view of the same; Fig. 3 a side elevational view of the roller shifting mechanism, the lower roller being elevated; Fig. 4 a view similar to Fig. 3, the lower roller being in its lowered position; Fig. 5 a plan view of the support for the lower roller; Fig. 6 an elevational view of the lower roller driving mechanism and Fig. 7 a cross-section on line 7—7 of Fig. 6.

Referring to the illustrative embodiment 25 of the invention, 1 represents the frame or standard of the machine adapted preferably for movable support on the floor. Projecting laterally from the upper part of the frame is a bracket 2 in which one end of a shaft 3 is revolubly supported, the opposite end of the shaft being supported in the frame. The upper or heating roll 3^a is secured to this shaft and is adapted to be heated in any suitable manner. A worm gear 4 within the frame is secured to the shaft and meshes with a worm 5 secured to a shaft 6 revolubly mounted on the frame and a pulley 7 is secured to a projecting end of the shaft 6. A belt 8 engaged with the pulley is also engaged with a pulley 9 secured to the shaft of an electric motor 10 or other source of power. A guard 11 encloses the pulleys and the belt.

A gear 12 also meshes with the worm 5 and is secured to a revolubly mounted shaft 13 which projects through the side wall 1^a of the frame. A gear 14 is secured to the projecting end of the shaft 13 and meshes with a gear 15 mounted on a stud 16 projecting from the wall 1^a. The gear 14 also meshes with a gear 17 mounted on a stud 18 projecting from a plate 19 that is loosely mounted on the shaft 13. A spring 20 is attached to the plate and to a stud or pin 21 that projects from the wall

1^a, and tends to rock the plate toward a stop 21^a (Fig. 3). The gear 17 is loosely pinned by the pins 17^a to a gear 22 also mounted on the stud 18, and the gear 22 is adapted to mesh with a gear 23 secured to a shaft 24 that is mounted in one arm 25^a of a bell crank 25 that is secured to a sleeve 26 revolubly mounted on shaft 27 that is fixed in a bracket 28 secured to the frame and projecting therefrom substantially parallel to the upper roll 3^a. The loose-pin connection between the gears 17 and 22 assures proper meshing of the gears 22 and 23, since the gear 22 may then stop or lag momentarily to permit the teeth of the gear 23 to properly engage gear 22 upon shifting the roll 30 toward the roll 3^a, thereby avoiding stripping of the gears 22 and 23. An arm 29 is secured to the opposite end of the sleeve 26 and supports the opposite end of the shaft 24. The lower roll 30 is secured or formed on the shaft 24. The lower roll is, therefore, swung on the fixed shaft 27. The shaft 27 is braced by a rod 27^a that is secured to the main frame and is connected at its upper end to the shaft by a bolt 27^b that extends through the said upper end of the rod and through an enlarged opening 26^a in the sleeve into a threaded opening in the shaft 27. The opening 26^a is large enough to permit the sleeve to rock on the shaft 27.

A link 31 is pivoted to the arm 25^b of the bell crank 25 and to one end of a band 32 disposed within a drum 15^a formed on or secured to the gear 15, a fabric or other friction band 33 being disposed between the band 32 and the annular wall of the drum. Lugs 34 are formed at opposite ends of the band 32 and between said lugs, and pivoted to a fixed plate 35 is a lever 36 having a cam 37 thereon that abuts both the lugs, and which cam, when the lever 36 is rocked in a proper direction, causes the lugs to separate to cause the friction band to grip the rotating drum sufficiently to cause the band 32 under the influence of the rotating drum to move clockwise a short distance to reciprocate the link 31 and rock the bell crank, the sleeve 26 and the arms 25 and 29 to cause the lower roll to approach or contact with the upper roll. A stop 38 is slidably mounted on the wall 1^a and beneath the lever 36 to adjustably control the downward movement of the said lever. The stop 38 engages on one or more pins 39 projecting

from the wall 1^a and it is adjusted longitudinally by the screw 40 attached to it and mounted in a lug 41 pivotally mounted on the plate 1^a. A rod 42 is suitably engaged at its upper end to the lever 36, the lower end of the rod being operatively connected to a suitable pedal 43, by the depression of which pedal the lever is rocked on its pivot.

Disks 22^a and 23^a are secured to or formed 10 on corresponding faces of the gears 22 and 23 which abut when the gear 23 is moved toward the gear 22. These plates prevent said gears from meshing too deeply and binding. When the gear 23 is out of mesh 15 with the gear 22, the plate 19 is moved clockwise by the spring as the gear drops and eventually abuts the stop 21^a.

A segment member 44 is pivotally mounted 20 on the plate 1^a and above the lever 36. A hand lever 45 is pivoted to the wall 1^a and a rod 46 is pivoted to both the disk and the lever. By depressing the hand lever the disk is swung into contact with the lever 36 to rock it just as the depression of the pedal 25 rocks the said lever, the slotted upper end of the rod 42 permitting the lever to move downwardly without reciprocating the rod.

It is to be noted that when the electric motor is operating the upper roll and the 30 gears 14, 15, 17 and 22 are continuously rotating. When the operator depresses the pedal the lever 36 is pulled downwardly into contact with the stop 38, which stop has been adjusted to limit the desired extent of such downward movement. This movement of the lever causes the clutch band to grip the rotating drum with sufficient force to cause the band to move with the drum (clockwise, Fig. 3). The link 31 35 travels with the band and rocks the bell crank 25 and the arm 29 to raise the lower roll toward the upper roll and into contact therewith, with such pressure as the controlled throw of the lever 36 permits. The gear 23 on the shaft of the lower roll is engaged at the same time with the rotating gear 22 and the latter gear and the plate 19 are swung upwardly on the shaft 13, the rotating gear 17 moving upwardly on the rotating gear 14. The grip of the clutch on the drum 15^a is not sufficient to prevent the drum from continuing its rotation when the movement of the band ceases.

When the pedal is released the lower roll 55 descends under the influence of gravity, the clutch mechanism releasing relatively slowly from the drum so that the roll descends without jar and the gear 23 freely disconnects from the gear 22. Since the gear 60 22 is pivotally supported on the main drive shaft 13, it assures of the meshing of the gears 22 and 23 irrespective of the degree of pressure of the lower roll on the upper roll or of the nearness of approach of the 65 lower roll to the upper roll.

A very refined control of the pressure to be exerted by the lower roll upon the upper roll is thus possible.

It will be noted that one driving member—the worm 5—drives both rolls through 70 the connecting gears, the bodily movable roll 30 having a gear 22 revolubly mounted on a pivotal support 19, as a part of its operative connection with the worm.

What I claim is:

1. In an ironing machine, the combination of two cooperating revoluble rolls one of which is bodily movable toward the other, a driven member, a member adapted to be driven by the driven member and having a pivotally mounted support, a revoluble drum and a member having operative connection to the bodily movable roll and adapted to frictionally engage the drum for causing the said roll to move toward the other roll and to cause it to operatively connect to the member having a pivotally mounted support.

2. In an ironing machine, the combination of two cooperating revoluble rolls one of which is bodily movable toward the other, a driven member, a revoluble drum driven by the driven member, a member driven by the driven member and having a pivotally mounted support, a friction member adapted to engage the drum and having a connection to the bodily movable roll, means to cause the friction member to engage the drum for causing the bodily movable roll to operatively engage the member having the pivotal support and to move toward the other roll and means to regulate the pressure between the two rolls when they are in contact.

3. In an ironing machine, the combination of two revolubly mounted rolls, one of which is bodily movable toward the other, a 105 driving shaft, a pivotally mounted support, a gear revolubly mounted on the support and adapted to be driven by the shaft, a gear having connection with the bodily movable roll, a revoluble member having driven connection with the shaft, a member adapted to frictionally engage the revoluble member and having an operative connection to the bodily movable roll, means to cause the friction member to engage the revoluble member 110 and cause the bodily movable roll to move toward the other roll and to cause the gear on said bodily movable roll to engage the gear carried by the pivotally mounted support, and adjustable means to limit the movement of the friction member.

4. In an ironing machine, the combination of two revolubly mounted rolls one of which is bodily movable toward the other, a gear having connection with the bodily movable 125 roll, a driving shaft, a gear secured to the shaft, a plate pivotally mounted on the shaft, means to swing the plate in one direction, a gear revolubly mounted on the plate and having driven connection with the gear on 130

- the shaft, a drum adapted to be rotated by the driving shaft, a friction band within the drum adapted to engage the same and having connection to the bodily movable roll, 5 a lever adapted to cause the band to frictionally engage the drum to cause the band to move bodily therewith for moving the bodily movable roll toward the other roll and for engaging the gear on said movable 10 roll with the gear on the plate and an adjustable stop adapted to be abutted by the lever.
5. In an ironing machine, the combination of two revolvably mounted rolls, a pivotal support for one of the rolls, a gear having connection with said latter roll, a driving shaft, a gear secured to the shaft, a pivotally mounted plate, means to swing the plate in one direction, a pair of gears revolvably mounted on the plate, one of which is engaged with the gear on the shaft and is loosely pinned to and drives the other gear of said pair, the said loosely pinned gear being adapted to be engaged by the gear on 25 the roll having the pivotal support, a revoluble drum having a driving connection with the driving shaft, a clutch mechanism within the drum, a link connected to the clutch mechanism and to the pivotal support, 30 a pedal operatively connected to the clutch mechanism for causing the mechanism to engage the drum and reciprocate the link and cause the roll having the pivotal support to move toward the other roll and connect 35 the first named gear to the loosely pinned gear.
6. In an ironing machine, a main driving
- shaft, a roll driven by said shaft, a pivoted support including a bell crank lever and a fixed shaft, a second roll revolvably mounted 40 on the fixed shaft, a train of gears driven by the main shaft, a gear on the second roll adapted to be connected to the train of gears, a revoluble drum having a driven connection to the main shaft, a friction band within the 45 drum, a reciprocable member connected to the friction band and to the bell crank, a member to cause the band to frictionally engage the drum and means to actuate the latter member whereby the reciprocable 50 member is reciprocated to cause the second roll to move bodily toward the other roll and the gear on the second roll is caused to engage the train of gears.
7. In an ironing machine, two cooperating 55 revolvably mounted rolls, a swinging frame carrying one of the rolls, a main driving shaft, gear mechanism connected to the shaft and adapted to be connected to the latter roll, a revolvably mounted drum having a 60 driving connection to the main shaft, a friction band within the drum, a reciprocable member connected to the band and to the swinging frame, and means to expand the 65 band into frictional engagement with the drum consisting of a cam, an arm connected to the cam, a pedal, a rod pivotally connected to the pedal and to the arm and an adjustable cam stop to regulate the movement 70 of the arm in one direction.

In witness whereof I have hereunto set my hand this 12th day of August, 1926.

THOMAS N. BROWN.
